SOLAR SPACE GAMES
Elmer M. Newhouse, 2582 Druid Park Drive,
Baltimore, Md.
Filed Mar. 1, 1960, Ser. No. 12,126
5 Claims. (Cl. 273—134)

This invention relates in general to games and, more particularly, to a solar space game.

It is an object of the invention to provide a game of chance which will at the same time impart to the players some information relating to the solar system.

A further object of the invention is to provide a solar space game including a game board, provided with suitable indicia for the various planets of the solar system and including a spinner wheel and dice for enabling the players to reach the various planets. Suitable flags, plastic coins and miniature space vehicles are also provided for use as indicators during the course of play.

Yet another object of the invention is to provide a solar space game which contains the elements of chance in its play, is well adapted for amusement purposes and yet, at the same time, has educational value.

The invention consists of the novel constructions, arrangements and devices to be hereinafter described and claimed for carrying out the above-stated objects and such other objects as will appear from the following description of preferred embodiments of the invention described with reference to the accompanying drawings, in which:

FIG. 1 represents the game board on which the solar space game is played;

FIGS. 2, 3, 4 and 5 represent green dice which are used to reach various of the planets;

FIGS. 6, 7 and 8 represent black dice which are used to reach the remaining planets;

FIG. 9 is a perspective of one of the novel dice;

FIGS. 10, 11 and 12 are scoring discs;

FIG. 13 shows one of the indicia used on the reverse side of the discs shown in FIGS. 10, 11 and 12;

FIG. 14 is a representation of a flag designating a particular player;

FIGS. 15 and 16 are side and front views, respectively, of a miniature space ship;

FIG. 17 is a top view of a spinner wheel used to reach the moon; and

FIG. 18 is a perspective of a scoring pad which may be used in lieu of the scoring discs set out in FIGS. 10, 11 and 12.

Like numerals refer to like parts throughout the various views.

Turning now to FIG. 1, the game board shown therein is a representation of the solar system. At the center of the system is sun 10, surrounded by planets mercury 11, venus 12, earth 13, including its moon 14, and mars 15. The aforementioned planets represent the so-called "inner" group. Moving out to the "outer" group, there is planet jupiter 16, saturn 17, uranus 18, neptune 19, and pluto 20. Each planet has the correct astronomical symbol represented thereon and, in addition, bears the name nearby along with the period to complete one revolution around the sun.

The game board further bears, for informative purposes only, a list of the nine planets and the sun and the moon with the correct astronomical figure adjacent thereto. Also on the board, is a "Time Schedule for Space Exploration," which represents the number of days it would take a space ship to reach the various planets from a space station on the moon.

FIGS. 2, 3, 4 and 5 represent face representation of dice 21, 22, 23 and 24, used to reach the aforementioned

2

"outer" group of planets. FIGS. 6, 7 and 8 are representations of dice 25, 26 and 27, used to reach the aforementioned "inner" group of planets.

In scoring the game, various points are awarded to the first player to reach a planet, to a second player to reach that particular planet, and to the third player to reach that particular planet. The point values awarded are 12, 7 and 5 respectively. In order to aid in keeping score, the scoring discs 28, 29 and 30, as set out in FIGS. 10, 11 and 12, are provided, there being one set of three discs for each planet. On the reverse side of each set of discs will appear the astronomical symbol for each of the nine planets, as shown on the game board. Disc 31, as shown in FIG. 13 for example, bears the astronomical symbol for mars.

Each player is given an identifying flag 32, as shown in FIG. 14. Each flag 32 comprises a base portion 33, a mast portion 34, and an identifying portion 35. It will be apparent that the various identifying portions 35 will be distinguished one from the other by any suitable color or delineation.

A miniature space ship 36, as set out in FIGS. 15 and 16, comprises a body portion 37 and a cabin portion 38. There will be one space ship 36 for each player, and it will be noted that the space ships will be differentiated similarly to the flags 32, so that each player will have his flag and space ship the same color and delineation.

A spinner wheel 39 is provided for reaching the escape velocity necessary to overcome the gravitational pull of the earth and enable the space explorer to reach the moon. The spinner wheel 39 comprises a wheel portion 40, inscribed with the numerals 1 through 12 thereon, and a rotating arrow 41, suitably mounted on a bearing 42, so that it may be spun on the wheel portion 40.

In keeping score, a scoring pad 43 is provided as an option to replace scoring discs 28, 29 and 30. Each sheet of the scoring pad bears the names of the planets in the left hand column 44 thereof, and opposite thereto a number of blank columns with space for the names of the players at the top of each column.

The object of the game is for a player to leave the earth and reach the moon, which is then used as a space station. Each player then attempts to reach the planets from the moon. Various points are awarded for the first, second and third player to reach each particular planet. After each planet has been reached by a player, that player must return to his base on the moon before he can travel to the next planet. When all of the planets have been visited by the various players, the game is over, with the winner being the player having the highest number of points. For a player to reach the moon from the earth, an escape velocity of at least 7 miles per second, or more, must be attained. Once on the moon, the dice are used to reach the various planets. The green dice to reach the "outer" group of planets, and the black dice to reach the "inner" group of planets.

In play, a player spins arrow 41 on spinner wheel 39. If the arrow points to 7, or any higher number, he has then reached an escape velocity sufficient to carry him away from the gravitational pull of the earth to the moon. He then moves his miniature space ship 36 to the vicinity of the moon. Each player, in turn, spins arrow 41 until such time as he is able to move his space ship to the moon. Dependent on whether one wishes to reach an "outer" planet or an "inner" planet, one throws the green dice or the black dice. In the "Time Schedule for Space Exploration" it will be noted, for example, that it takes 105 days to reach mercury. If a player is attempting to reach this particular planet, he throws the black dice. If the numerals 1—0—5 appear uppermost on the dice after they have stopped rolling, the particular player may then move his space ship to mercury, receiving 12 points for

being the first player to reach the planet. He is then given a disc 30, bearing the numeral 12 thereon, with the reverse side having the correct astronomical symbol for the planet mercury, as set out in the list of astronomical symbols on the game board. To return from mercury to the moon, he must again throw the black dice until the numerals 1-0-5 appear, after which he moves his space ship back from mercury to the moon, leaving his flag 32 on the planet to indicate that he has been there. He is then free to try for any other planet.

As a further example, if a player were to try to reach the planet neptune, 3007 astrons are required according to the "Time Table for Space Exploration." An "astron" is merely a convenient unit to use, since the number of days required would be astronomical. Using the green dice then, the player must continue to throw each time his turn is reached until the numerals 3-0-0-7 appear uppermost on the dice, at which time he is free to move his space ship to the planet. As before, the same dice must be thrown with the same numerals uppermost for return to the moon, at which time the particular player's flag will be left on the planet. In order to secure the greatest number of points, it will be apparent that each player would attempt first to reach a planet that had not previously been reached by another player, so that he may secure the 12 points for being the first. At the same time, it will be apparent that any one player may not only be the first to reach the planet, but also the second and third, in which case one player could receive the total of 24 points for reaching any one planet three times. When all the planets have been reached by at least one player, as indicated by the fact of a flag on each planet, the game is over. Each player then counts his discs 28, 29 or 30, as the case may be, with the player having the greatest number of points declared the winner of the game.

It will be apparent that I have provided a game with the various elements of chance, suspense, some element of skill, and one which is adapted for whiling away many a pleasant hour. At the same time, the particular players will be given an introduction to the solar system, which has educational benefits. These benefits comprise learning the various planets of the system, and also act as a stimulus to further knowledge.

I wish it to be understood that my invention is not to be limited to the specific constructions and arrangements shown and described, except only insofar as the claims may be so limited, as it will be apparent to those skilled in the art that changes may be made without departing from the principles of the invention.

What is claimed is:

1. Game apparatus comprising a playing board having a representation of the solar system thereon, said representation comprising the sun at the center thereof and the solar system planets represented as being in orbit around the sun, said orbits being spaced radially outwardly according to their position in the solar system; a space station for space travel on the board; said game apparatus including a chance device having associated therewith a plurality of different indicia, and comprising means for selecting by chance one of said indicia, said indicia representing different velocities, some of which are arbitrarily designated as "escape" velocities enabling a player to move his game piece to the space station; said game apparatus also including a member having thereon a schedule in units of time for space exploration setting out the time required to travel from the space station to the various planets, each of a first group of said planets having travel

times comprising a first set number of digits, and each of a second group of said planets having travel times comprising a second differing set number of digits; said game apparatus further including a first set of dice having digits 5 therein including those on the time schedule for space exploration whereby a player may leave the space station for space exploration to said first group of planets, the number of dice in said set being equal to the number of digits in said first set of digits; and a second set of dice having digits thereon including those on the time schedule for space exploration whereby a player may leave the space station for space exploration to said second group of planets, the number of dice in said second set being equal to the number of digits in said second set of digits, said first and second sets of dice being differentiated from each other for selection and use in travel to either the first group of planets or the second group of planets.

2. Game apparatus comprising a playing board having a representation of the solar system thereon, said representation comprising the sun at the center thereof and the solar system planets represented as being in orbit around the sun, said orbits being spaced radially outwardly from the sun according to their position in the solar system, said representation further including a space station depicted by the earth's moon; said game apparatus including a spinner wheel having associated therewith a plurality of different indicia, and comprising means for selecting by chance one of said indicia, said indicia representing different velocities, some of which are arbitrarily designated as "escape" velocities enabling a player to move his game piece to the space station; said game apparatus also including a member having thereon a schedule in units of time for space exploration, said schedule setting out the time required to travel from the moon to the various planets, each of a first group of said planets having travel times comprised of three digits, and each of a second group of said planets having travel times comprised of four digits; said game apparatus further including a first set of three dice having digits thereon including those on said time schedule whereby a player may leave the moon for space exploration to said first group of planets; and a second set of four dice having digits thereon including those on said time schedule whereby a player may leave the moon for space exploration to said second group of planets, said first and second sets of dice being differentiated from each other for selection and use in travel to either the first group of planets or the second group of planets.

3. Game apparatus as set out in claim 2 further including a plurality of space ships, one for each player and separately differentiated.

4. Game apparatus as set out in claim 3 further including a plurality of marker flags differentiated similarly to said space ships.

5. Game apparatus as set out in claim 4 further including a plurality of sets of scoring discs, one said set for each planet other than earth.
